UNITED STATES PATENT OFFICE.

CARL B. GRAHL AND HARRY H. GRAHL, OF COUNCIL BLUFFS, IOWA.

SHEET-METAL ROOFING.

SPECIFICATION forming part of Letters Patent No. 508,105, dated November 7, 1893.

Application filed May 13, 1893. Serial No. 474,124. (No model.)

To all whom it may concern:

Be it known that we, CARL B. GRAHL and HARRY H. GRAHL, citizens of the United States, residing at Council Bluffs, in the county of Pottawattamie, State of Iowa, have invented certain new and useful Improvements in Sheet-Metal Roofing, of which the following is a specification, reference being had therein to the accompanying drawings.

10 This invention relates to certain new and useful improvements in sheet metal roofing, and it has for its objects among others to provide a simple and cheap form of roofing by which the sheets can be quickly and easily secured in place and the joint formed in such a manner as to be secure and tight. The cap piece is so formed as to embrace the tongue of one sheet and then after the next sheet has been placed in position a portion 20 of the same cap piece is bent thereover and the whole clamped together.

Other objects and advantages of the invention will hereinafter appear and the novel features thereof will be specifically defined 25 by the appended claim.

The invention is clearly illustrated in the accompanying drawings, which, with the letters of reference marked thereon, form a part of this specification, and in which—

30 Figure 1 is a perspective view showing two sheets in position with the cap piece partly closed down. Fig. 2 is a perspective view showing portions of two sheets with their tongues or flanges and a portion of the cap piece, the parts being separated. Fig. 3 is a vertical cross section through the joint.

Like letters of reference indicate like parts throughout the several views.

Referring now to the details of the drawings by letter, A designates a sheet metal shingle or plate having one edge turned up at a right angle to form the flange or tongue a, and B is a similar plate having its edge adjacent to the flange of the plate A also 45 turned up at a right angle to form the tongue or flange b.

C is the cap piece; it is formed with a horizontal flange c which is adapted to receive the nails or other means by which it is secured to the roof, and with a vertical portion c' which is bent upon itself at its upper edge as seen at c² and thence extended downward

as seen at c³, leaving a space c⁴ for the reception of the flange a of the plate A as seen in Fig. 1 and then bent upon itself as shown at 5: c⁵ and extended upward a distance above the bend c² to form the overlapping portion D, which may be cut as seen at d so that it may be more easily turned down into the position shown at the right of Fig. 1. The edge of 60 this overlapping portion is beaded or strengthened by the same being turned over as seen at d'.

In use the plate A is first placed in position and then the cap piece is placed over it 65 as will be understood from Fig. 2 in which the cap piece is just about being placed in position, the space c⁴ receiving the flange a of said plate and the flange c being adapted to lie flat upon the roof to which it is secured 70 in any of the well known ways; the plate B is then placed in position with its flange b against the vertical portion c' of the cap piece as shown in Fig. 1, the plate B being crimped as seen at e at the edge of the flange 75 c, and then the portion D of the cap piece is turned over so as to embrace the flanges a and b of the plates A and B and the vertical portions of the cap piece, and the whole is then pressed together in any suitable manner 80 to bind the parts firmly together.

What is claimed as new is—

The combination with two sheets, each with a flange and one of them crimped, as at e, of a cap-piece having a horizontal portion 85 fitted within the crimp, a vertical portion arranged between the flanges of said sheets, a bend embracing the upper edge of one of said flanges, a doubled vertical portion upon the outside of the embraced flange and a 90 downwardly-extending portion embracing both flanges and the central vertical portion of the cap piece and covering the upper edges thereof and of the central fold, the said cap piece being provided with a bead at its free 95 edge and slotted at the upper folded edge, substantially as specified.

In testimony whereof we affix our signatures in presence of two witnesses.

CARL B. GRAHL.
HARRY H. GRAHL.
